FLOOR CONSTRUCTION AND METHOD OF
PROVIDING SAME

Sidney Dreier, New York, and Samuel Lubash, Bayside, N.Y. (both % Dreier Structural Steel Co., 32-50 Vernon Blvd., Long Island City 6, N.Y.)
Filed Apr. 22, 1960, Ser. No. 24,148
4 Claims. (Cl. 50-83)

This invention relates to improvements in floor construction and methods for providing the same. More particularly, this invention relates to improvements in poured concrete floor construction and method of providing the same.

It is an object of this invention to provide a structure for pouring concrete floors which is economical and lends itself to mass production.

It is another object of this invention to provide a method for pouring concrete floors which is economical and lends itself to mass pouring of concrete floors.

It is a further object of this invention to provide a structure and method for pouring concrete floors which can be performed by unskilled labor.

Other objects will appear hereinafter.

For the purpose of illustrating the invention there is shown in the drawings forms which are presently preferred; it being understood, however, that this invention is not limited to the precise arrangements and instrumentalities shown.

FIGURE 1 is a cross-sectional view of applicants' floor construction in an intermediate stage.

FIGURE 2 is a cross-sectional view of an I-beam and the form support of applicants' invention.

FIGURE 3 is a perspective view of a support bracket and anchor clip of applicants' invention.

FIGURE 4 is a cross-sectional view of an alternate embodiment of applicants' invention.

FIGURE 5 is a cross-sectional view of an alternate embodiment of applicants' invention.

FIGURE 6 is a cross-sectional view of an alternate embodiment of applicants' invention.

FIGURE 7 is a cross-sectional view of an alternate embodiment of applicants' invention.

Referring now to the drawing in detail, where like numerals indicate like elements, there is shown in FIGURE 1 a cross-sectional view of applicants' floor construction in an intermediate stage.

There is shown in FIGURE 1 a plurality of I-beams 12, 12' and 12" which are disposed in parallel relation in a horizontal plane. As is conventional in the art, the I-beams are supported at their extremities. Each of the I-beams 12, 12', and 12" and their form supports are identical. Therefore, it is deemed sufficient to describe only one of these I-beams in detail.

Referring to FIGURE 2, it will be seen that I-beam 12 comprises a web 14 and parallel flanges 16 and 18. Web 14 is provided with a pair of holes 20 at spaced points therealong. At the various locations of the holes 20 along the I-beam 12 there are provided a pair of supporting brackets 22 and 24. Since the supporting brackets 22 and 24 are identical, only bracket 24 will be explained in detail.

Referring to FIGURE 3, it will be seen that supporting bracket 24 is generally L-shaped. The longer leg of the bracket 24 is designated by the numeral 26 and the shorter leg is designated by the numeral 28. It will be noted that the shorter leg 28 of the bracket 24 has a pair of holes 30 therethrough. The spacing of the holes 30 in bracket 24 corresponds to the spacing of holes 20 in the web 14 of the I-beam 12. The shorter leg 28 of the bracket 24 is provided with a channel 34 which extends throughout its length. An anchor clip 36 is

2

mounted in channel 34 for a purpose disclosed hereinafter. It will be noted that the anchor clip 36 is of a length appreciably greater than the length of arm 28 of bracket 24. At its extremities, bracket 36 is provided with outwardly extending flanges 38 and 40. Flange 40 is provided with a short inwardly directed lip 42.

Supporting brackets 22 and 24 are securely fixed to the web portion 14 by bolts 32 as shown in FIGURE 2. Bolts 32 have shank portions which pass through holes 30 in the support brackets and holes 20 in the web portion. As shown in FIGURE 2, bolts 32 clamp the supporting brackets 22 and 24 to the web portion 14 on opposite sides thereof with the anchor clip 36 disposed in the channel 34 of each of the supporting brackets 22 and 24. It will be noted that the longer arm 26 of the supporting brackets is horizontally disposed and that the shorter arm 28 is vertically disposed. The flange 40 on the anchor clip 36 is of sufficient width so as to support the lower extremity of the shorter arm 28 between the lip 42 and the upstanding body portion of the anchor clip. As mentioned above, the supporting brackets 22 and 24 are disposed at spaced points along the length of the web portion 14. Extending along the length of the I-beam 12 on opposite sides of the web portion 14 there is provided a form support 44 which is supported in a horizontal plane by support brackets 22 and 24. The anchor clip 36 is of sufficient length so that the flange 38 slips over the uppermost surface of the form support 44.

Each of the I-beams 12, 12', and 12" is provided with identical support brackets 22 and 24 and form supports 44. Intermediately disposed between adjacent I-beams there are provided forms 48. Each of the form supports 44 is provided at its outer extremity with a shoulder 46 which supports the ends of forms 48. To prevent the forms 48 from moving relative to the form supports 44 there is provided a filler 50 on the shoulder 46. Filler 50 may be of metal, wood, or plastic. It will be seen that forms 48 will support the bulk of the poured concrete and as a result tend to pivot the form supports 44 with relation to the supporting brackets 22 and 24. The flanges 38, 40, and 42 of the anchor clip 36 prevent any pivoting movement between form support 44 and supporting brackets 22 and 24. If desired, reinforcement 52 is provided with portions disposed above and below flange 16 of I-beam 12.

The operation for pouring the concrete floor is as follows.

50 I claim:

The I-beams 12, 12' and 12" are supported at their extremities and disposed in parallel horizontal disposition. The supporting brackets 22 and 24 with the anchor clip 36 disposed within the channel 34 of the supporting brackets are bolted to the web portion 14 of each I-beam at spaced points along the length of each I-beam. Form supports 44 are disposed on each side of the web portion of each I-beam with the form support disposed between the flange 38 on the anchor clip 36 and the horizontally disposed arm 26 of the brackets 22 and 24. Forms 48 are placed between adjacent I-beams and supported on the form supports 44. Filler material 50 is then inserted to prevent relative movement between forms 48 and form supports 44. The reinforcement 52 is disposed as shown in FIGURE 1 and then the concrete is poured over the reinforcement 52, flange 16 of the I-beams, and onto the forms 48. Before the concrete has set, the upper surface of the floor will be made smooth by any well known manner. After the concrete has had sufficient time to dry, the bolts 32, supporting brackets 22 and 24, form support 44, and forms 48 are removed.

The above process is repeated until all of the concrete floors in the building have been poured.

Referring to FIGURE 4, there is shown an alternate embodiment of applicants' invention. The embodiment of FIGURE 4 is substantially the same as the embodiment in FIGURE 2 except for the securing means which holds the supporting brackets 22' and 24' in assembled relation with the web portion 14'. At spaced points along the length of web portion 14', there are provided a pair of supporting brackets 22' and 24' which are affixed to the web portion 14' by threaded studs 56 which are driven through the supporting brackets 22' and 24' and into the web portion 14' by an explosive charge. The apparatus for shooting the threaded studs 56 is of conventional construction and very popular in the construction field. The use of threaded studs 56 and the apparatus for shooting the same eliminates the necessity for drilling holes in the web portion of the I-beam and in the supporting brackets. Since there are no bolts or bolt holes, the use of threaded studs 56 lends itself to more rapid assembly of the supporting brackets and the web portion of the I-beam.

The operation of the embodiment shown in FIGURE 4 is the same as the embodiment disclosed above. After the concrete has dried and the supporting structure has been disassembled, the threaded studs 56 will be thrown away.

FIGURE 5 discloses another embodiment of applicants' invention. I-beam 58 is provided having end flanges 62 and 64. It will be noted that the end flanges 62 and 64 have tapered surfaces 66 on their inner sides thereof. Supporting brackets 68 and 70 are provided with tapered bottom surfaces 72 which are supported on the tapered surface 66 of the end flange 62. Each of the supporting brackets 68 and 70 is provided with a channel 74 which extends inwardly from one end of the supporting brackets 68 and 70. It will be noted that the channel 74 has a length which is less than the length of the supporting brackets 68 and 70. At one end of the supporting brackets 68 and 70 there is provided a transverse slot 76. Within the channels 74 there are provided anchor clips 78. Each anchor clip 78 is provided with upstanding flanges 80 and 82. Each of the anchor clips 78 is disposed within the channels 74 of supporting brackets 68 and 70. The flange 82 of the anchor clip 78 is disposed within slot 76 in each of the supporting brackets 68 and 70. A pair of form supports 83 are provided, one of each form supports being disposed on opposite sides of the web 60 of the I-beam 58. Each form support 83 is mounted in a horizontal position on the bracket supports 68 and 70 with the anchor clip flange 80 disposed above the uppermost surface of each form support. Between adjacent I-beams there are provided forms 84 which have their extremities resting on opposed form supports 82.

To prevent relative movement between the form supports 83 and the forms 84, there are provided fillers 85. A C-clamp 86 is provided for maintaining the supporting brackets 68 and 70 in assembled relationship against the web portion 60 of the I-beam 58. As shown, the C-clamp is of conventional construction and need not be discussed in detail.

The operation of this embodiment of applicants' invention is substantially the same as the embodiment shown in FIGURE 2. The provision of a C-clamp as the securing means has certain advantages over the embodiment shown in FIGURE 2. It will be noted that use of a C-clamp precludes the necessity for drilling holes in the supporting brackets and the web portion of the I-beam.

FIGURE 6 discloses another embodiment of applicants' invention which is substantially the same as the embodiment shown in FIGURE 5. The I-beam 88 shown in FIGURE 6 is of the same type as the I-beam shown in FIGURE 2. The I-beam 88 differs from the I-beam 58 by having the inner surfaces of the end flanges 89

and 90 parallel to one another. Therefore, the supporting brackets 68' and 70' have parallel end surfaces. The supporting brackets 68' and 70' are secured to the I-beam 88 by bolts 91 which pass through holes in the supporting brackets and the web portion of the I-beam 88. The anchor clips 78, the form supports 83, and the forms 84 are exactly identical with the showing in FIGURE 5.

FIGURE 7 discloses another embodiment of applicants' invention. The I-beam 12, the supporting brackets 22 and 24, and the bolt 32 are substantially the same as shown in FIGURE 2. The form support 93 differs from the form support in any of the previous embodiments since its width is less than the width of the supporting brackets 22 and 24. Thus, it will be noted that this embodiment does not use an anchor clip. The form supports 93 and 95 extend longitudinally along the length of the I-beam 12 and are disposed on opposite sides of the web portion 14. Disposed in horizontal parallel relation and extending between adjacent I-beams there are provided form joists 96 and 98 which are supported at their extremities by form supports 93 and 95. The forms 48 are horizontally disposed on the upper surface of the form joists 96 and 98. Alternatively, the form joists 96 and 98 could rest directly on the bracket supports 22 and 24.

The operation of this embodiment is substantially the same as set forth above. The use of form joists 96 and 98 permits this embodiment to be used where heavier floors are required or where it is desired to space the I-beams a greater distance apart from one another.

In each of the embodiments shown in FIGURES 2, 6, 7, it is possible to eliminate the necessity for drilling a hole through the web portion of the I-beam. In this case, studs having threaded ends would be disposed on opposite sides of the web portion and welded thereto with the threaded ends extending radially outward. The studs would extend through holes in the support brackets and a nut would be provided on the threaded end of the stud so as to hold the support brackets in assembled relationship with the web portion of the I-beam.

The present invention may be embodied in other specific forms without departing from the spirit or essential attributes thereof and, accordingly, reference should be made to the appended claims, rather than to the foregoing specification as indicating the scope of the invention.

It is claimed:

1. A floor construction comprising a plurality of support members, support brackets disposed on opposite sides of a web portion of each support member at spaced points along the length of each support member below the top of each support member, means removably securing the support brackets to the web portion of each support member, a form support on each support bracket, anchor clip means removably securing each form support to its respective support bracket, forms extending between adjacent support members having their ends supported by opposed form supports, a slab of poured concrete disposed over said forms and enveloping the portion of each support member above said form supports, said form supports being disposed in a horizontal parallel relationship, the distance between the ends of each form being less than the distance between opposed brackets, the width of said form supports and support brackets being taken in the direction between parallel support members, and each form support being wider than its respective support bracket.

2. A floor construction comprising a plurality of support members, a support bracket disposed on opposite sides of a web portion of each support member at spaced points along the length of each support member below the top of each support member, means removably securing the support bracket to the web portion of each support member, a form support on top of each support bracket, anchor clip means removably securing each form support to its respective support bracket, forms extending between adjacent support members having their ends

supported by opposed form supports, a slab of poured concrete disposed over said forms and enveloping the portion of each support member above said form supports, said anchor clip means including an upstanding body portion disposed within a groove in each of said brackets, a first flange on said body portion being disposed on the uppermost surface of said form supports and a second flange on said body portion being in contact with a surface on said brackets, said bracket surface being perpendicular to the web portion of each of said support members.

3. A floor construction comprising a plurality of I-beams, a support bracket disposed on opposite sides of a web portion of each I-beam at spaced points along the length of each I-beam below the top of each I-beam, means removably securing the support brackets to the web portion of each I-beam, a form support on each support bracket, anchor clip means removably securing each form support to its respective support bracket, forms extending between adjacent I-beams having their ends supported by opposed form supports, a slab of poured concrete disposed over said forms and enveloping the portion of each I-beam above said form supports, said anchor clip means comprising clips, each clip having substantially parallel portions overlying a portion of said form support and said bracket, said form supports being provided with notches along the edge furthest from said I-beam web portion, each end of said forms being disposed in the notch on its respective form support.

4. A floor construction comprising a plurality of support members, a support bracket disposed on opposite sides of a web portion of each support member at spaced points along the length of each support member below the top of each support member, means removably securing the support brackets to the web portion of each sup-

port member, a form support on top of each support bracket, anchor clip means removably securing each form support to its respective support bracket, forms extending between adjacent support members having their ends supported by opposed form supports, a slab of poured concrete disposed over said forms and enveloping the portion of each support member above said form supports, each of said brackets being provided with a channel in the face opposed to the web portion, said anchor clip means including an anchor clip in each channel, a slot in each bracket at one end of the channel, each slot extending in a direction away from the web portion of the support members, each bracket having a first flange extending into the slot of the bracket adjacent thereto, a second flange on said anchor clips extending over a portion of the uppermost surface of the form supports.
